UNITED STATES PATENT OFFICE.

CHARLES L. PARKER, OF SEATTLE, WASHINGTON, ASSIGNOR TO VIOLET E. PARKER,
OF SEATTLE, WASHINGTON.

SOAP HOLDER.

Application filed September 2, 1924. Serial No. 735,449.

My invention aims to provide a simple and inexpensive, yet a practical and desirable device which is designed primarily for holding a cake of soap, enabling the user to 5 conveniently apply such soap to his back when bathing, although it will be understood that the device may also be used for other purposes, for instance, for holding wash cloths, mop cloths, scrubbing brushes, 10 brushes of other sorts, etc.

With the foregoing in view, the invention resides in the novel subject matter herein-after described and claimed, the description being supplemented by the accompanying 15 drawing.

Figure 1 is a plan view of a soap holder constructed in accordance with my invention.

Figure 2 is a longitudinal sectional view 20 on line 2—2 of Fig. 1.

Figures 3 and 4 are transverse sectional views as indicated by lines 3—3 and 4—4 of Fig. 1.

Figure 5 is a side elevation showing a 25 slightly different form of construction.

In the construction shown in Figs. 1, 2, 3 and 4, the numeral 1 designates an elongated handle which is preferably curved in a convenient manner. Carried by the front 30 end of this handle and disposed at any desired angle with respect thereto, is an article-holding frame 2. At least this frame, but preferably the frame and the handle also, may be made from a single strip of spring 35 metal. In the construction shown, this metal strip is bent to provide two parallel handle-forming reaches 3, and at the front end of the handle, is further bent to provide front and rear parallel bars 4 and 5 which are 40 adapted to grip a cake of soap 6 or any other article to be held and manipulated by the device, the strip being additionally bent to provide a pair of enlarged spring loop portions 7 which connect the ends of the bars 4 and 5 and are disposed in a common plane 45 with said bars. These spring loops exert a constant force to move the bars 4 and 5 toward each other, so as to effectively clamp any article which may be placed between 50 them, and as indicated in Fig. 1, the ends of this article may extend into the spring loop portions. Preferably, the bars 4 and 5 have inwardly stamped projections 8 to engage

the article and prevent slippage thereof. For the purpose of stiffening the handle-forming reaches 3 and providing a rounded handle formation, these reaches may well be transversely curved away from each other as shown in Fig. 4, throughout the greater part of their lengths. In the construction shown, 55 this transverse curvature ceases at a point spaced from the frame 2, and between such curvature and frame, the terminals 9 and 10 of the spring metal strip are secured together in any suitable manner, for instance, 60 by spot welding or by rivets 11.

While the construction above described 65 may well be followed, it is to be understood that modifications may be made and that the handle 1 need not extend from the frame 70 2 at the exact point or angle illustrated, it being well within the scope of the invention to locate this handle in the most convenient location, according to the uses to which the device is to be put. It may also be stated 75 at this point, that the handle may be pivotally and adjustably connected to the article-holding frame. This has been illustrated in Fig. 5, in which a frame 2^a has been shown, 80 which may be considered as constructed in the same manner as the frame 2, except that the terminals 9^a of the spring metal strip do not assist in forming the handle 1^a, but merely project from the frame a sufficient 85 distance to provide ears to which said handle may be connected by a clamping bolt 11^a which is preferably provided with a wing-nut 12^a. By loosening the nut, the handle 90 may be swung to any desired position with respect to the frame 2^a and it may be held in such position by again tightening the nut. As in the form of the invention previously 95 described, it will be understood that the handle may extend from the frame at any desired angle and point.

The device may be effectively used for holding a cake of soap to soap one's back when bathing, may then be used to hold a bath brush or a wash cloth to complete the washing operation, and it will also be clear 100 that the invention may be constructed in a manner to adapt it for holding numerous other articles, such as mop cloths, wall or floor brushes, etc.

As excellent results may be obtained from 105 the general construction shown, it is pref-

erably followed, but within the scope of the invention as claimed, modifications may be made.

I claim:

5. 1. A soap holder comprising a handle and an article-holding frame carried thereby, said frame consisting of a pair of parallel article clamping bars, and enlarged spring loop portions connecting the ends of said bars in a common plane therewith for moving them toward each other, said spring loop portions being capable of receiving the ends of an article held between said bars.
10. 2. A soap holder comprising a handle, and an article-holding frame carried thereby, said frame being formed of a single spring metal strip bent to provide a pair of parallel article-clamping bars and enlarged spring loop portions connecting the ends of said bars for moving them toward each other.
15. 3. A soap holder comprising a single strip of spring metal having parallel reaches

forming a handle, the strip being bent at the front end of said handle to provide parallel article-clamping bars, and enlarged spring ²⁵ loop portions connecting the ends of said bars for moving them toward each other.

4. A soap holder comprising a single strip of spring metal having parallel reaches forming a handle, the strip being bent at the ³⁰ front end of said handle to provide parallel article-clamping bars and enlarged spring loop portions connecting the ends of said bars and disposed in a common plane with the latter for drawing said bars toward each ³⁵ other.

5. A structure as specified in claim 3; said parallel reaches of the strip being transversely curved away from each other to stiffen them and to provide a rounded ⁴⁰ handle.

In testimony whereof I have hereunto affixed my signature.

CHARLES L. PARKER.
